(57) **CLAIM**

The ornamental design for a pergola, as shown and described.

DESCRIPTION

FIG. 1 is a perspective view of a pergola in the combination of component 1 and component 2, showing my new design; FIG. 2 is a perspective view with the top part of FIG. 1 being opened;

FIG. 3 is a front, right and top perspective view of component 1 of a pergola;

FIG. 4 is a rear, left and bottom perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is a front, left and top perspective view of component 2 of a pergola;

FIG. 12 is a rear, right and bottom perspective view thereof;

FIG. 13 is a front view thereof;

FIG. 14 is a rear view thereof;

FIG. 15 is a left side view thereof;

FIG. 16 is a right side view thereof;

FIG. 17 is a top plan view thereof;

FIG. 18 is a bottom plan view thereof;

FIG. 19 is an enlarged view of portion of FIG. 2 thereof;

FIG. 20 is an enlarged view of portion of FIG. 3 thereof;

FIG. 21 is an enlarged view of portion of FIG. 3 thereof;

FIG. 22 is an enlarged view of portion of FIG. 3 thereof;

FIG. 23 is an enlarged view of portion of FIG. 4 thereof; and,

FIG. 24 is an enlarged view of portion of FIG. 4 thereof.

The broken lines shown in the drawings illustrate portions of the pergola that form no part of the claimed design.
